UNITED STATES PATENT OFFICE.

GEORGE ROBERT KELTNER, OF PHOENIX, ARIZONA, ASSIGNOR OF ONE-HALF TO WALTER TALBOT, WILLIAM S. HEFLIN, AND CARL E. MILLER, ALL OF PHOENIX, ARIZONA.

SASH BALANCE AND LOCK.

1,129,688.

Specification of Letters Patent.

Patented Feb. 23, 1915.

Application filed February 25, 1914. Serial No. 820,881.

To all whom it may concern:

Be it known that I, GEORGE R. KELTNER, a citizen of the United States, and a resident of Phoenix, in the county of Maricopa and State of Arizona, have made certain new and useful Improvements in Sash Balances and Locks, of which the following is a specification.

My present invention relates to sash fasteners and balances, my object being to provide a combined sash balance and lock which will be simple in construction, durable in use and readily and easily operated to produce the desired results.

15 In the accompanying drawings, forming a part of my invention, Figure 1 is a vertical longitudinal section taken through a portion of a sash and its frame and through my improvements mounted in connection therewith. Fig. 2 is a horizontal section taken therethrough, and, Fig. 3 is a vertical transverse section taken therethrough.

20 Referring now to these figures, the upper and lower sashes are indicated at A and A' respectively, each of these sashes being provided along one side edge with a metallic strip a and a plurality of apertures a' arranged in a vertical series and extending also through this strip.

25 The inner portion B' of the window casing B is provided with slots b through which project one side of toothed wheels C, the teeth of which engage within the openings a' above mentioned so that the wheels 30 C will be rotated when the sashes are raised and lowered.

35 The wheels C have their hubs c rotatably mounted upon inwardly projecting tubular members D secured at their outer ends to the 40 angular side portions E' of a supporting plate E secured to the inner surface of the casing portion B' before mentioned. The toothed wheels C being thus movably mounted are controlled in their movement by 45 means of springs F coiled about their hub portions c, before mentioned, and having the inner ends thereof secured to the said hub portions and having the outer ends thereof secured to bolts f carried by the angular portions E' of the supporting plates, 50 these springs being so arranged as that the sashes will be substantially balanced in all positions of adjustment.

55 Journaled through the tubular members D is the inner portion of a stem G, the outer

portion of which extends through the inner side wall of the casing B and is provided with a handle or knob G' by means of which the stem may be rotated. As clearly seen, the inner portion of the stem G is provided 60 with oppositely projecting actuating lugs g and g', located at a point between the two toothed wheels and disposed above the upper angular ends h of vertically movable rods H, these rods being extended through 65 apertures in the upper angular portion i of a plate I secured to the plate E and provided with angular side portions i'.

The lower ends of rods H are pivotally connected to the upper curved engaging portions j of angular levers J intermediately pivoted at j' and having their lower ends connected by a retractile coil spring K, the function of which is to draw the lower ends 70 of the levers toward one another and cause 75 their upper ends to move upwardly into engagement with the teeth of the wheels C as best shown in Figs. 1 and 3.

Thus from the foregoing it will be seen 80 that to raise the inner sash A', it is simply necessary to turn the stem G toward the left in Fig. 2, by grasping its handle G', lug g bearing down upon the respective rod H and effecting the release of the respective lever J from its toothed wheel C. The sash 85 is then free to be raised and lowered as desired, the respective spring F effecting a balance at all times. As soon as the stem G is released, the sash will be immediately relocked through the action of spring K which 90 returns the parts to the positions shown.

I claim:

1. In a device of the character described, the combination of window sashes provided with notched edges, of independent revolvable toothed wheels engaging the notches of the sashes, tubular members upon which the said wheels are journaled, a supporting plate having portions to which the said tubular members are secured in axially 100 alined relation, controlling springs connected at one end to the toothed wheels and at their opposite ends to the supporting plate, a stem journaled through the tubular portions and provided with a handle upon 105 its outer end, oppositely projecting lugs secured upon the stem at a point between the toothed wheels, intermediately pivoted levers engageable at one end with the toothed wheels, a spring connecting the opposite 110

ends of the said levers whereby to maintain the same in engaged position, actuating rods connected to the levers and movable to disengage the levers from the toothed wheels, 5 said actuating rods having upper angular ends disposed beneath the said lugs of the stem, for the purpose described.

2. In a device of the character described, the combination of a sash having a notched 10 side edge, a toothed wheel disposed in engagement with the notches of the sash, a balance spring controlling the toothed wheel, a spring controlled lever having one end normally in engagement with the 15 toothed wheel at the lower part thereof, a vertically movable member pivotally connected at its lower end with the lever, and a member mounted to turn and having a projection adapted to engage the upper end of 20 said vertically movable member to move the latter and release the lever when it is desired to raise and lower the sash.

3. The combination with window sashes having notched sides, and a casing in which 25 the sashes are mounted to slide, having slots opposite the notched portions of the sashes, independent revoluble toothed wheels mounted in the casing and projecting through the slots thereof to engage the 30 notched sides of the sashes, balance springs

having connection with the said toothed wheels, spring controlled levers normally in engagement with the said toothed wheels, actuating members connected with the levers and a single member having means for 35 moving the actuating members and independently releasing the said levers, all for the purpose described.

4. The combination with a window sash, and a slotted casing in which the sash is 40 mounted to slide, of a toothed wheel mounted in the casing and projecting through said slot, the said sash being provided at its side with means for engagement by the teeth of said wheel, whereby the wheel will be rotated when the sash is raised and lowered, a balance spring connected with the toothed wheel, a spring-controlled angular lever having its upper end normally in engagement with the teeth of said wheel, an actuating rod having vertical guided movement and connected with the said lever, and a stem mounted to turn and provided with a laterally projecting member for engaging and moving the said actuating rod to release 50 the said lever.

GEORGE ROBERT KELTNER.
